LOCKING BOLT FOR DOORS

Filed June 22, 1928

Inventor
W.S. Torrence,

Fig. 3.

By Charles O'Brien, Attorney

UNITED STATES PATENT OFFICE.

WALTER S. TORRENCE, OF NEW YORK, N. Y.

LOCKING BOLT FOR DOORS.

Application filed June 22, 1928. Serial No. 287,454.

The present invention relates to door locks and fasteners and has for its principal object to provide the locking bolt operable through a key actuated lock for sliding the bolt into a position permitting the opening of the door.

A further object of the invention is to provide a sliding bolt for doors operable for movement into door releasing position through a key inserted in the lock at the outside of the door and provided with independent manually operable means at the inner side of the door for moving the bolt into position for opening or closing the door.

15 A still further object of the invention is to provide a sectional locking bolt of this character which extends in a horizontal position entirely across the door at the inner side thereof and providing a pivotal connection for the sections of the bolt and arranging the pivot points for movement into a position adjacent the hinged edge of the door when the bolt is moved into door releasing position so as to permit the swinging 25 of the door in the usual manner.

An additional object is to provide a device of this character of simple and practical construction, which is strong and durable, efficient and reliable in performance, 30 relatively inexpensive to manufacture and install in operative position and otherwise well adapted to the purpose for which the same is intended.

Other objects and advantages reside in the 35 special construction, combination and arrangement of the various elements forming the invention as more fully hereinafter described and claimed, reference being had to the accompanying drawings forming part 40 hereof, wherein like numerals refer to like parts throughout, and in which:

In the drawings:

Figure 1 is a view in elevation showing the device positioned at the inside of a door 45 and shown in locked position,

Figure 2 is a horizontal sectional view through the door taken along a line immediately above the locking bolt and

50 Figure 3 is a fragmentary vertical sectional view through the door, and the lock housing.

Referring now to the drawing in detail, wherein for the purpose of illustration I have disclosed a preferred embodiment of 55 my invention, the numeral 5 designates a

door of conventional construction and mounted along one vertical edge by hinges 6 upon a door frame 7.

An opening 8 is formed in the door adjacent the swinging edge thereof and within 60 which is fitted a lock housing 9 having an escutcheon plate 10 formed thereon and positioned at the outside of the door and within which plate is formed an opening for receiving a key 11.

65 The key is adapted to operate in a rotatably mounted lock member 12 positioned in the housing, said member having a shaft 12' extending from the inner end and protruding from the door at the inner side thereof.

To the inner surface of the door is attached a housing 13 through which the shaft extension 12' is inserted, the portion of the shaft extension within the housing being provided with a spur gear 14 engaging a rack 15 75 formed along the upper edge of a bar or door bolt 16.

The bolt 16 is disposed horizontally with respect to the door and is slidably disposed in a groove 17 formed in the housing, the bolt being of sufficient length to extend entirely across the door and overlapping the vertical side edges thereof. At each side of the door frame 7 is arranged a guide bracket 18 through which the opposite ends 85 of the bolt are slidably inserted.

Thus when the bolt is extended across the inner side of the door with its opposite ends disposed within the brackets 18 and each side of the frame, the door is secured against opening movement.

90 The bolt 16 is constructed of a pair of sections of unequal length, the shorter section 19 being disposed at the end of the bolt adjacent the hinged edge of the door, the adjacent end 95 of the section being connected by a pivot pin 20 disposed vertically so as to permit horizontal swinging movement of one of the sections of the bolt relative to the other.

A guide bracket 20 is also secured to the 100 inner side of the door through which the bolt 16 is slidably inserted, the bracket being positioned so that the pivoted ends of the sections of the bolt are disposed within the bracket when the bolt is arranged in door securing 105 position as clearly illustrated in Figure 1 of the drawing, whereby to prevent movement of the sections on the pivot.

The position at which the sections of the bolt are pivoted is further regulated so that 110

upon the sliding of the bolt 16 through the operation of the key 11 and gear and rack engagement 14 and 15 respectively, the pivotal connection between the sections of the bolt 5 will be moved sufficiently to occupy a position in vertical alinement with the hinged edge of the door and thus prevent interference with the opening movement of the door by the bolt. The lock mechanism provided in the present 10 embodiment of the invention is adapted to operate the bolt only from the outside of the door in order to arrange for the movement of the bolt into door releasing position from the inner sides of the door a sleeve 22 is formed 15 integrally with the gear 14, the sleeve extending outwardly of the housing 13 with its outer end formed into a head 23 which constitutes a push button by means of which the gear 14 may be pushed inwardly of the housing out of 20 engagement with the rack 15.

A coil spring 24 is arranged on the shaft extension 12' for engaging the gear 14 and normally urging the same outwardly with respect to the shaft extension for engagement 25 with the rack.

If desired a similar spring 25 may be positioned upon the sleeve 22 and compressed between the outer face of the housing and the head 23 of the sleeve to assist the spring 24 in 30 also normally retaining the gear in engaged position with the rack.

A slotted opening 26 is formed in the housing 13 through which a handle 27 extends having one end connected with the bolt 16 35 whereby to permit a person at the inside of the door to slide the bolt out of door securing position upon the pressing of the head 23 inwardly as to release the gear from the rack.

It will be apparent from the foregoing that 40 the bolt cannot be forced by persons at the outside of the door or otherwise moved into

door opening position except through use of the key 11 provided for operating the lock.

It is obvious that my invention is susceptible to various changes and modifications in 45 construction without departing from the spirit of the invention or the scope of the appended claim, and I accordingly claim all such forms of the device to which I am entitled. 50

Having thus described my invention, what I claim as new is:

A door fastener comprising a sectional bolt 55 slidably mounted at the inside of the door with its opposite end disposed in overlapping relation with the opposite edges of the door and with the sections of the bolt pivotally connected for horizontal swinging movement, said pivotal connection being arranged for movement into a horizontal position at the hinged edge of the door upon the movement of the bolt into door releasing position, a key actuated locking member rotatably mounted in the door and having a shaft extension 60 formed at its inner end and protruding from the inner side of the door, a gear 65 slidably mounted on said shaft extension and adapted for rotation with the locking member, said bolt having a rack formed thereon engageable with the gear, and means disposed inwardly 70 of the door for moving the gear out of rack engaging position permitting the actuation of the bolt independent of said locking member, said means comprising a sleeve 75 slidably mounted on said shaft extension and connected at one end with said gear, a head formed at the outer end of the sleeve, spring means engageable with the gear whereby to normally retain the same in engaged position and an operating handle formed on said bolt. 80

In testimony whereof I affix my signature.
WALTER S. TORRENCE.
